UNITED STATES PATENT OFFICE.

EDWIN P. BUGEE, OF VERNON, NEW YORK.

SUTURING INSTRUMENT.

Application filed December 5, 1921. Serial No. 520,038.

To all whom it may concern:

Be it known that J. EDWIN P. BUGEE, a citizen of the United States, and a resident of Vernon, in the county of Oneida and State of New York, have invented certain new and useful Improvements in Suturing Instruments; and I do hereby declare that the following is a full, clear, and exact description thereof, which will enable others skilled in the art to which it appertains to make and use the same, reference being had to the accompanying drawings, and to the reference numerals marked thereon, which form part of this specification.

15 My present invention relates to a suturing instrument meaning thereby surgical apparatus for sewing flesh or other body tissue.

The purpose of my invention is to provide an improved suturing instrument which is simple in construction and operation, efficient in action and adapted for use in a large variety of circumstances.

20 A further purpose is to provide a suturing instrument which is especially adapted for use in restricted cavities or confined locations and which can be placed in such positions and readily, effectively and safely manipulated in such locations.

25 A still further purpose is to provide an instrument of the class described wherein the needle is entirely enclosed in a casing or cavity before the instrument is inserted into or brought near the body and in which the needle is passed from such holding cavity into a receiving cavity between the jaws of the receiving forceps without any possibility of its being accidentally brought into contact at either end with any other tissue than the portion of tissue grasped between the 30 flesh-engaging faces of the flesh-grasping forceps of the instrument.

35 A further purpose is to provide an instrument of the class described wherein the threaded needle is securely housed in a cavity or casing forming a part of the needle-delivering forceps before the instrument is applied to the body and wherein the needle-receiving forceps are firmly but detachably fastened to the needle-delivering forceps before the instrument is brought into actual operation so that the needle will stay in initial position until positively operated and then will be positively grasped by the needle-receiving forceps; furthermore an

object is to produce an instrument wherein the travel of the needle is definitely directed as to its course and amount and then positively grasped by part of the apparatus.

Another object is to provide a pair of flesh-grasping forceps having thereon means for initially holding the needle and moving it forward through the tissue with certainty as to direction and extent of motion and also to provide the same parts in combination furthermore with means for grasping the needle with certainty and positiveness after the needle has been passed through or substantially through the tissue being operated upon.

A further object is to provide an apparatus of the character described of such construction, form and operation that it may be used effectively and safely in any position or at any angle and with a minimum of or even absence of sight of the parts being operated upon.

A still further advantage is to provide an instrument of the class described which is adapted to operate in a very small cavity on account of the parts being very compact and closely assembled at the operating end and on account of the curved formation of the jaws as they extend back from the points of the jaws to the pivot of the forceps.

Fig. 1 is a top or plan view of the complete suturing instrument assuming the instrument to be in the relative position there indicated so as to pass the needle from the right hand to the left hand side of the instrument during the sewing operation. It will be understood that for clearness and convenience of description and illustration in the drawings and specification the instrument is in this position (except where expressly otherwise stated). It is obvious, however, that the instrument may in practice be turned on its general longitudinal axis or otherwise so as to perform the suturing operation in any direction desired.

In Fig. 1 the jaws of the flesh-grasping and needle-delivering forceps A are in closed position and the needle-operating mechanism is in withdrawn position ready for operation. In this view also the jaws of the needle-receiving forceps B are shown attached to the back of the co-operating jaw of the other forceps A.

Fig. 2 is a top or plan view of the flesh-

grasping and needle-delivering forceps A in the same position shown in Fig. 1 and Fig. 3 is a left hand side view of the said forceps.

Fig. 4 is a plan view of the needle and 5 thread used in the instrument.

Fig. 5 is a horizontal cross sectional view 10 on an enlarged scale of the jaws of both pairs of forceps with the needle in position but with only the projecting ends of the thread shown.

Fig. 6 is a view similar to Fig. 5 but with the needle-delivering mechanism moved forward so that the needle has been pushed over into the needle-receiving forceps B ready to 15 be seized by the jaws of the needle-receiving forceps B.

Fig. 7 is a vertical cross sectional view 20 on an enlarged scale of the jaws both pairs of forceps along the axis 7—7 as seen in the direction indicated by the arrows.

Fig. 8 is a similar view showing only the jaws of the needle-receiving forceps B.

Fig. 9 is a similar view showing only the 25 left hand jaw of the needle-delivering forceps A.

Fig. 10 is a top or plan view of the needle-receiving forceps B.

Fig. 11 is a right hand edge view of the 30 same with jaws open ready to receive the needle.

Fig. 12 is an end view of the handle parts only of the same forceps.

Fig. 13 is a right hand edge view on an 35 enlarged scale of the jaws of the needle-receiving forceps in the open position ready to receive the needle.

Fig. 14 is a view similar to Fig. 13 but with the jaws closed tightly on the needle.

Fig. 15 is a vertical cross sectional view 40 on an enlarged scale along the axis 15—15 showing the jaws of the needle-receiving forceps in the open position.

Fig. 16 is a similar view showing the jaws closed tightly on the needle.

45 Referring to the drawings in a more particular description it will be seen that the suturing instrument consists of two main parts, one the flesh-grasping and needle-delivering forceps A and the other the 50 needle-receiving forceps B. The forceps A consist of two main members 20 and 21 crossing each other and pivoted to each other by pivot screw 22 resulting in the member 20 having a jaw 23 and a long handle 24 and 55 the member 21 having a jaw 25 and long handle 26. Preferably near their extremities the handles 24 and 26 will be provided with thumb and finger rings 27 and 28 respectively common to surgical instruments. The opposing faces 23^a of the jaw 23 and 25^a of the jaw 25 form the flesh or tissue grasping faces of the entire instrument. In all of the drawings these faces are 60 shown without tissue intervening therebetween but it will be obvious that they may be

brought together upon enclosed tissue or flesh to the desired extent and with considerable pressure if desired and held together upon the flesh by means of interlocking detachable catches 29 and 30 provided upon the 70 handles 24 and 26 near the finger rings.

The jaw 23 is provided with an aperture 75 31 extending from its flesh-grasping face 23^a entirely through the jaw to the outer or left hand face of the jaw as the parts are seen in Figs. 1, 2, 5 and 6. This aperture allows the needle 32 and its thread or suture 33 to be passed through said jaw.

At the right hand face 23^a the aperture is only slightly larger than the needle 80 which passes through it. At a point back from face 23^a say about one-third the thickness of jaw 23 the aperture is much larger and then tapers to a smaller diameter at 85 the left hand face of the jaw as shown in Fig. 9.

This tapering shape is for the purpose of providing means to detachably secure to this jaw the jaws of the needle-receiving forceps B as will be hereinafter described. The extending of the face 23^a 90 to provide only a hole large enough for the passage of the needle therethrough provides a guard to prevent the ends 47^a and 49^a of the needle-receiving jaws engaging or pinching the flesh as the jaws of the 95 needle-receiving jaws are forced together.

The jaw 25 is enlarged so as to extend a considerable distance back from its flesh-engaging face 25^a in the form of a casing 34 having provided therein a curved or 100 arc shaped cavity 35 the casing being generally in the form of a curved cylinder with one end of its cavity 35 extending to the flesh-grasping face 25^a and the other end 105 open to receive the needle-operating plunger 36.

This plunger 36 at all times has its forward end 36^a within the cavity 35 and the 110 whole length of the plunger is curved to fit the curve of the needle cavity 35. The plunger is pivotally mounted so as to have its forward end pushed forward through the greater extent of the needle cavity 35 by means of the rear end 36^b of the plunger being secured to a block 37 generally triangular in shape as more particularly shown in Figs. 5 and 6. This block is pivotally mounted near one corner to the jaw 25 by pin 38 placed at the center of the curve of the cavity 35. To the right hand corner of the block 37 as seen in Figs. 2, 5 and 6 by means of pin 39 there are pivoted the forward extremities of a forked operating push rod 40 the free end of which rod extends out past the finger rings 27 and 28 far enough for convenient manipulation. Preferably the swinging block 37 is mounted in a recess formed in the middle portion of the jaw 25 with the rear end of the plunger 36 secured to the 120 125 130

third corner of said triangular block. The plunger then extends forward past the pivoting point 39 with the plunger farther out than said pivot 39 and between the two 5 forks of the push rod 40. The push rod 40 is slidingly mounted towards its outer end in an eye 41 which holds the rod generally in place upon the instrument but allows its forward end to make the slight swinging 10 movement necessary to forward and backward travel.

Back of the flesh-engaging face 25^a of the jaw 25 said jaw is formed with a rearwardly facing recess 42 so that when the 15 threaded needle 32 is placed into the cavity 35 through the aperture 43 in the flesh-engaging face 25^a, the thread or suture 33 extending from the eye in the rear end of the needle will extend out through said 20 recess 42 so that when the needle is pushed forward from the cavity 35 through the aperture 43 in jaw 25 and through the tissue between the flesh-engaging jaws of these forceps and with its point passed 25 through the aperture 31 in the jaw 23 the free end of the thread will be upon the right hand side of the tissue being operated upon. It will be understood that the needle 32 is bent or curved to conform generally 30 to the curve of the cavity 35 and that this curved formation of the needle and its cavity and the casing 34 is to enable the instrument to have as compact a head as possible in order that it may be used in 35 small cavities.

The needle-receiving forceps consist of a pair of main members 44 and 45 crossing each other and pivoted to each other by pivot screw 46 resulting in the member 44 40 having a relatively short jaw 47 and relatively long handle 48 and resulting similarly in member 45 having a short jaw 49 and a relatively long handle 50. Preferably the extremities of the handles 48 and 45 50 will be provided with the usual finger rings 51 and 52.

The axis of the pivoting screw 46 of the needle-receiving forceps B is at right angles to the axis of the pivot screw 22 of the 50 needle-delivering forceps A when the two parts are attached to each other for operation. Furthermore the attachment and arrangement of the parts is such that the forward ends of the jaws 47 and 49 of the 55 needle-receiving forceps are securely but detachably attached to the outer side of the left hand jaw 23 of the needle-delivering forceps with the jaw 49 above the jaw 47 as the parts are seen in Fig. 1.

60 A practical and the preferred form of so positively but detachably securing the extremities of the jaws of the needle-receiving forceps to the jaw 23 of the needle-delivering forceps is to have the extremities 49^a and 47^a 65 of the said jaws 49 and 47 enlarged or

tapered outwardly as they approach the extreme end of the jaw so as to fit the undercut formation of the aperture 31 in the jaw 23 as more plainly appears in Figs. 7, 8, 9, 13 and 14. The arrangement and proportion 70 of parts is such that when the jaws 47 and 49 of the receiving forceps B are closed the extremities 47^a and 49^a may be passed into the aperture 31 of the jaw 23 of the forceps A; then by moving the jaws apart the extremities 47^a and 49^a are wedged into the undercut aperture 31 thus holding the jaws 75 of the receiving forceps securely attached to the delivering forceps as long as the jaws 47 and 49 remain apart which incidentally is the needle-receiving position for said forceps B. The jaws of the forceps B are thus held apart by means of a finger 80 53 on the outer end of the handle 48 being sprung into a recess in the outer end of an oppositely disposed finger 54 on the handle 50. Upon the finger 54 may also be provided a pair of spring clips 55 adapted to 85 yieldingly engage the rearwardly projecting end 56 of the handle 24 and thus hold the handle end of the forceps B in the right position relative to jaw 23 and its handle 24 even though the other jaw 25 and handle 26 of the needle-delivering forceps are being moved. 90

The operation of the complete device will be as follows assuming the two forceps to be already separated from each other: The push rod 40 will be withdrawn to the necessary extent thereby withdrawing the plunger 36 to the rear end of the cavity 35; then a needle 32 with thread or suture 33 in its eye at the rear end will be passed point first through recess 42 and aperture 43 and then backed rear end first through aperture 43 into the needle-receiving cavity 35 thus leaving the free end of the thread extending out from the recess 42. Then the needle-receiving forceps will be attached to the left hand jaw 23 of the forceps A as already mentioned with the jaws 47 and 49 of the needle-receiving forceps open as far as allowed by the recess 31 thus securing the forward end of the forceps A to the jaw 23. At the same time the handle end of these forceps will be attached to the rearward projecting end 56 of handle 24 by means of spring clips 55. The instrument is now ready to be placed in contact with the tissue to be sewed. The jaws 23 and 25 of the needle-delivering and flesh-grasping forceps are moved apart sufficiently to grasp the tissue to be sewed and are then brought together upon the tissue to be sewed and held in such grasping position by the engagement of its fingers 29 and 30. Forward movement of the push rod 40 pushes the plunger 36 forward which in turn pushes the needle point foremost from the cavity 35 through the tissue grasped between the 115

120 125 130

jaws 25 and 23 well into the curved pocket provided between the open jaws 47 and 49 of the needle-receiving forceps B. The handles of the needle-receiving forceps are then 5 sprung apart a little to disengage the fingers 53 and 54 and then the jaws of the needle-receiving forceps are brought together firmly upon the middle of the needle. By this motion the extremities 47^a and 49^a 10 of the jaws 47 and 49 are released from the jaw 23 and may be withdrawn therefrom bringing the needle the rest of the way through the tissue.

Preferably, however, before withdrawing 15 the jaws of the needle-receiving forceps from the jaw 23 of the other forceps the jaws of the needle-receiving forceps will be locked in closed position securely upon the needle therebetween by hooking the pointed 20 catch 57 on finger 53 of handle 48 into one of the notches 58 on the opposing finger 54. Then the forceps B may be safely disengaged from the forceps A without danger of losing 25 the needle. The forceps B are disengaged by withdrawing the extremities 47^a and 49^a from the recess 31 of jaw 23 and moving the jaws of forceps B to the left enough to clear the needle from the tissue. The forceps B are then moved rearwardly 30 so as to slip the spring clips 55 off from the rearward point 56 of handle 24 or without such rearward movement of the forceps B the spring clips 55 may be sprung apart enough to disengage them from the point 35 56. As the forceps B are drawn away the thread or suturing material is drawn through the tissue resulting in the needle end of the thread projecting from the aperture 31 in jaw 23 on the left side of the tissue while 40 the other end of the thread extends through the aperture 43 in jaw 25 and out through the recess 42. The forceps B are now opened releasing the needle and are laid aside. The needle-delivering forceps are then opened 45 and may be withdrawn entirely leaving opposite ends of the suture upon the opposite sides of the tissue. Preferably, however, the forceps A may be further conveniently used to complete the tying of the knot or knots 50 in the suture. For this operation the end of the thread which has the needle on it is slipped out from aperture 31 in the jaw 23 and a single knot or a surgeon's knot is tied. The needle end is then run back 55 through aperture 31 of jaw 23 and both ends of the thread are held in one hand and the knot is pushed back into place and drawn tight by opening the jaws 23 and 25 of the forceps. Two or more knots may be tied 60 in a similar manner after which the long ends of the thread or catgut may be cut off leaving the completed thread or suture in place. It will be noted particularly that when the device is loaded with the threaded 65 needle and ready for operation the needle

is entirely enclosed within the casing 34 and that the needle stays thus guarded until it is pushed forward from the cavity 35 of said casing 34 into the curved pocket between the jaws of the receiving forceps B. 70 When withdrawn from the body the point and the greater length of the needle is thus entirely enclosed between the jaws of the forceps B. It will thus be seen that there is no danger of the needle injuring any 75 surrounding tissue or becoming lost or disengaged from the instrument.

It will be further noted that the receiving forceps are positively secured to the jaw 23 of the other forceps when the instrument is 80 brought into contact with the tissue and remain in this relative position until the forceps B are to be removed. For this reason the sewing operation of the instrument can always be completed in any position to 85 which the surgeon can apply the instrument at the beginning of the operation. In other words there is no possibility of getting the needle through the tissue and then finding that the needle cannot be reached or drawn 90 the rest of the way through the tissue.

Recess 42 makes a place for the thread as it is crowded out of cavity 35.

What I claim as new and desire to secure by Letters Patent is:

1. In a suturing instrument, the combination of a pair of flesh-grasping and needle-delivering forceps and a pair of needle-receiving forceps, the first jaw of the needle-delivering forceps being extended away from its flesh-engaging face to provide a needle-holding cavity opening to the flesh-engaging face, the second jaw of the needle-delivering forceps having means for detachably fastening thereto the jaws of the needle-receiving forceps and means for forcing the said needle forward from said holding cavity and into the space between the receiving jaws of the needle-receiving forceps. 100

2. In a suturing instrument, the combination of a pair of flesh-grasping and needle-delivering forceps and a pair of needle-receiving forceps, the first jaw of the needle-delivering forceps being extended away from its flesh-engaging face to provide a needle-holding cavity opening to the flesh-engaging face, the second jaw of the needle-delivering forceps having means for detachably fastening thereto the jaws of the needle-receiving forceps in open position and means for forcing the said needle forward from said holding cavity and into the space between the receiving jaws of the needle-receiving forceps. 115

3. In a suturing instrument, the combination of a pair of flesh-grasping and needle-delivering forceps and a pair of needle-receiving forceps, the first jaw of the needle-delivering forceps being extended away from its flesh-engaging face to provide a 125

95

105

110

115

120

125

130

needle-holding cavity opening to the flesh-engaging face, the second jaw of the needle-delivering forceps having means for detachably fastening thereto the jaws of the needle-receiving forceps said needle-receiving forceps being released from the second flesh-grasping jaw when the jaws of the needle-receiving forceps are moved to closed position and means for forcing the said needle forward from said holding cavity and into the space between the jaws of the needle-receiving forceps.

4. In a suturing instrument, the combination of a pair of flesh-grasping and needle-delivering forceps and a pair of needle-receiving forceps, the first jaw of the needle-delivering forceps being extended away from its flesh-engaging face to provide a needle-holding cavity opening to the flesh-engaging face, the second jaw of the needle-delivering forceps having means for detachably fastening thereto the jaws of the needle-receiving forceps in open position said needle-receiving forceps being released from the second flesh-grasping jaw when the jaws of the needle-receiving forceps are moved to closed position and means for forcing the said needle forward from said holding cavity and into the space between the jaws of the needle-receiving forceps.

5. In a suturing instrument, the combination of a pair of flesh-grasping and needle-delivering forceps, a casing adjacent to the flesh engaging face of one jaw of the needle-delivering forceps having a needle-holding cavity extending to the flesh-engaging face of said jaw, a plunger mounted to move to and fro in said cavity and force the needle forward from said cavity through the flesh-engaging jaws and operating means connected to said plunger.

6. In a suturing instrument, the combination of a pair of flesh-grasping and needle-delivering forceps, a casing adjacent to the flesh-engaging face of one jaw of the needle-delivering forceps having a needle-holding cavity extending to the flesh-engaging face of said jaw, a plunger mounted to move to and fro in said cavity and force the needle forward from said cavity through the flesh-engaging jaws, operating means connected to said plunger and means for holding the jaws of the flesh-grasping forceps in closed position.

7. In a suturing instrument, the combination of a pair of flesh-grasping and needle-delivering forceps, a pair of needle-receiving forceps, a casing adjacent to the flesh-engaging face of one jaw of the needle-delivering forceps having a needle-holding cavity extending to the flesh-engaging face of said jaw, a plunger mounted to move to and fro in said cavity and force the needle forward from said cavity through the flesh-engaging jaws and into the jaws of

the needle-receiving forceps and operating means connected to said plunger.

8. In a suturing instrument, the combination of a pair of flesh-grasping and needle-delivering forceps, a pair of needle-receiving forceps, a casing adjacent to the flesh-engaging face of one jaw of the needle-delivering forceps having a needle-holding cavity extending to the flesh-engaging face of said jaw, a plunger mounted to move to and fro in said cavity and force the needle forward from said cavity through the flesh-engaging jaws and into the jaws of the needle-receiving forceps, operating means connected to said plunger and means for holding the jaws of the flesh-grasping forceps in closed position.

9. In a suturing instrument, the combination of a pair of flesh-grasping and needle-delivering forceps, a pair of needle-receiving forceps, a casing adjacent to the flesh-engaging face of one jaw of the needle-delivering forceps having a needle-holding cavity extending to the flesh-engaging face of said jaw, a plunger mounted to move to and fro in said cavity and force the needle forward from said cavity through the flesh-engaging jaws and into the jaws of the needle-receiving forceps, operating means connected to said plunger and means for detachably holding the jaws of the receiving forceps in open position adjacent to the second jaw of the flesh-grasping forceps.

10. In a suturing instrument, the combination of a pair of flesh-grasping and needle-delivering forceps, a pair of needle-receiving forceps, a casing adjacent to the flesh-engaging face of one jaw of the needle-delivering forceps having a needle-holding cavity extending to the flesh-engaging face of said jaw, a plunger mounted to move to and fro in said cavity and force the needle forward from said cavity through the flesh-engaging jaws and into the jaws of the needle-receiving forceps, operating means connected to said plunger and means for positively holding the jaws of the receiving forceps in open position adjacent to the second jaw of the flesh-grasping forceps, said means allowing the receiving jaws to be detached when moved from open position.

11. In a suturing instrument, the combination of a pair of flesh-grasping and needle-delivering forceps, a pair of needle-receiving forceps, a casing adjacent to the flesh-engaging face of one jaw of the needle-delivering forceps having a needle-holding cavity extending to the flesh-engaging face of said jaw, a plunger mounted to move to and fro in said cavity and force the needle forward from said cavity through the flesh-engaging jaws and into the jaws of the needle-receiving forceps, operating means connected to said plunger, means for holding the jaws of the flesh-grasping forceps in

- closed position and means for detachably holding the jaws of the receiving forceps in open position adjacent to the second jaw of the flesh-grasping forceps.
12. In a suturing instrument, the combination of a pair of flesh-grasping and needle-delivering forceps, a pair of needle-receiving forceps, a casing adjacent to the flesh-engaging face of one jaw of the needle-delivering forceps having a needle-holding cavity extending to the flesh-engaging face of said jaw, a plunger mounted to move to and fro in said cavity and force the needle forward from said cavity through the flesh-engaging jaws and into the jaws of the needle-receiving forceps, operating means connected to said plunger, means for holding the jaws of the flesh-grasping forceps in closed position and means for positively holding the jaws of the receiving forceps in open position adjacent to the second jaw of the flesh-grasping forceps, said means allowing the receiving jaws to be detached when moved from open position.
13. In a suturing instrument the combination of a pair of flesh-grasping and needle-delivering forceps having apertures in each jaw for the passage of the needle therethrough, a needle-enclosing casing extending back from one jaw of the forceps and having a recess back of the jaw for the passage of the thread and means for pushing

the needle forward from the casing through the flesh-engaging jaws.

14. In a suturing instrument the combination of a pair of flesh-grasping and needle-delivering forceps having apertures in each jaw for the passage of the needle therethrough, a pair of needle-receiving forceps having a pocket between the jaws thereof to receive the needle, a needle-enclosing casing extending back from one jaw of the needle-delivering forceps and having a recess back of the jaw for the passage of the thread and means for pushing the needle forward from the casing through the flesh-engaging jaws and into the pocket between the jaws of the needle-receiving forceps.

15. In a suturing instrument the combination of a pair of flesh-grasping and needle-delivering forceps having apertures in each jaw for the passage of the needle therethrough, a pair of needle-receiving forceps having a curved pocket between the jaws thereof to receive the needle, a needle-enclosing casing extending back from one jaw of the forceps in a curve and means for pushing the needle forward from the casing through the flesh-engaging jaws and into the curved pocket between the jaws of the needle-receiving forceps.

In witness whereof I have affixed my signature, this 15th day of November 1921.

EDWIN P. BUGBEE.
